UNITED STATES PATENT OFFICE

JAMES CHARLES RALLS, OF SHEFFIELD, ENGLAND

LOCK

Application filed April 26, 1928, Serial No. 273,030, and in Great Britain May 26, 1927. Renewed March 28, 1931.

This invention relates to locks of the kind employing a series of adjacent sliding lever plates held friction tight and adapted to be operated about a common pivot by a key, each plate having an aperture for accommodating the key and nibs on the key being arranged to act one on each plate at the sides of the aperture so as to move adjacent plates in opposite directions, and each plate having a slot for the engagement and disengagement of a locking stump or tongue carried by a slidable member also operable by a nib on the key.

The object of this invention is to provide an improved lock of this kind.

A lock made according to this invention comprises a casing, a plurality of lever plates pivotally mounted in the casing and movable adjacently in opposite directions about their common pivot under the action of a key, a slidable member positioned adjacent one of the plates and provided with a stump or tongue, slots in the plates adapted to coincide on one position of the plates so as to permit engagement by the stump or tongue, and to be out of coincidence on any other position of the plates, twin bolts pivoted to the lock casing and operable so as to close on to and open away from one another across a staple receiving opening in the lock casing, means on the slidable member for operating the pivoted twin bolts on movement of the slidable member, a key receiving aperture in each plate and the slidable member, means on the casing for positioning a key, the plates and the slidable member being operable by nibs on the key acting on the sides of the apertures, the arrangement being such that adjacent plates move radially in opposite directions and the sliding member moves longitudinally with respect to the lock casing.

The invention will be better understood on reference to the accompanying drawings in which:

Fig. 1 is an inside elevation of one form of lock made in accordance with this invention and showing the twin locking bolts open.

Fig. 2 is a similar view showing the twin bolts closed.

Fig. 3 is a detail view showing the slidable member.

Fig. 4 is an end view of same.

Fig. 5 is a vertical section taken centrally through Fig. 2.

Figs. 6, 7 and 8 show forms of keys for operating the type of lock made according to this invention.

Fig. 9 is an elevation of a lever plate adapted to be spring pressed within the lock casing. *a* is the casing of the lock, *b*, *b* are the lever plates pivotally mounted about a common pivot *c* and having slots *d* for the engagement and disengagement of the tongue or stump *e* of a slidable member *f*. This slidable member is positioned by the pivot pin *c* engaging a slot *g* at one end of the said member. Pivotally mounted to pivots *g*' on the lock casing beyond the outer end of the lever plates *b* are two opposing bolt members *h*, *h* which are each provided with a locking or bolting stem *j* and rearwardly disposed lugs *j*', said members *h* being operated by pegs *k* on the slidable member *f* so as to close against or open away from each other across a staple receiving opening *i*. The position of the pegs *k* is such that after they have moved upward and closed the opposing bolt members *h* on to each other, said pegs take up a position between the side of the lock and the back of the opposing bolt members and thereby offer great resistance to any attempt at forcing the bolt members open by levering them with an extraneous implement. *m* is the guide for the key *n*.

The key is provided with a number of nibs *o* according to the number of lever plates *b* employed, one nib being provided for each plate and adapted to operate against the sides of its apertures *p* and an additional nib *q* for moving the slidable member *f* so that the tongue *e* thereon is made to engage or disengage the slots *d*. For closing the lock the key first operates the slidable member *f* so that the tongue *e* thereon is withdrawn from the slots *d*, the pegs *k* meanwhile operating the twin bolts *h* so as to close them against each other across the staple receiving opening *i* and subsequently assuming their position between the rear of the twin bolts *h* and the side of the lock casing *a* as shown in Fig. 2, thus wedging said bolts against opening movement. As the tongue *e* leaves the slots

d the nibs *o* operate adjacent lever plates in opposite directions so that the slots *d* are disposed out of register. For opening the lock, the lever plates *b* are first operated to 5 cause the slots *d* to register whereupon the slidable member is then actuated and its tongue enters the slots *d*, the pegs *k* meanwhile acting on the rear lugs *j'* of the twin bolts *h* operating them so as to open them.

10 To facilitate the use of thin lever plates *b* whereby reasonably thick and strong key nibs *o* may be utilized, said lever plates may be spaced apart by a washer or spacing member *s* located between each adjacent plate so 15 that a large enough space intervenes between each plate for the passage of thick nibs *o* and a very convenient washer to employ is one formed of a single member bent upon itself to lie astride the pivoted end of a 20 plate *b* so as to constitute two spacing members *s* as seen in Fig. 5. Alternatively the plates *b* may be formed thicker at their ends than at their middle to create the space for the key nibs and said ends thereby having 25 surface union contact.

30 Where a minimum of three plates *b* are employed the surface union principle of one unit frictionally contacting between two units is effected and no springs need be employed to act on the plates *b* but where only 35 one or only two plates *b* are employed for economical reasons it is preferable to provide for the said plate or plates to be spring pressed and this is effected by providing a 40 spring *t* which is secured in a slit *v* at the pivoted end of the plate *b* and which spring is constrained by bearing against the side of the lock casing *a*. The springs *t* of adjacent plates *b* are arranged at alternate sides 45 of the plates and the plates are thereby normally held in opposite relation so that their slots *d* are out of coincidence.

What I claim and desire to secure by Letters Patent is:—

45 A lock of the kind specified comprising a casing, a plurality of lever plates mounted about a pivot pin fixed to the casing, said lever plates having opposing contact faces approximately centrally of their structure 50 for engagement by an extraneous key, said lever plates being movable radially thereby adjacently in opposite directions both inwardly and outwardly of one another, a member longitudinally slidable over the pivot 55 pin and between one of said lever plates and a face of the lock casing, interengaging means between the slidable member and the lever plates operable at a determinable position of the lever plates, opposed twin locking 60 members pivoted to the lock casing and operable within the structural limits thereof 65 across a staple receiving opening in said lock casing, laterally projecting means on the slidable member for operating in its movement 70 said twin locking members, said means being

arranged to take up a position between the twin locking members and a side of the lock casing when said locking members are closed across the staple receiving opening, the slidable member having a key receiving aperture 75 providing walls for engagement by a key and key positioning means on the lock casing.

Signed at Sheffield in the county of York, England this 27th day of March A. D. 1928.

JAMES CHARLES RALLS.
